ATTORNEY

UNITED STATES PATENT OFFICE.

JOHN L. BORSCH, OF PHILADELPHIA, PENNSYLVANIA.

EYEGLASSES.

SPECIFICATION forming part of Letters Patent No. 410,233, dated September 3, 1889.

Application filed March 23, 1889. Serial No. 304,482. (No model.)

To all whom it may concern:

Be it known that I, JOHN L. BORSCH, a citizen of the United States, residing at Philadelphia in the county of Philadelphia and 5 State of Pennsylvania, have invented certain new and useful Improvements in Eyeglasses, of which the following is a specification, reference being had thereto to the accompanying drawings.

10 This improvement relates to that class of eyeglasses provided with nose-pieces distinct from the frame; and the invention consists in the peculiar construction, arrangement, and combination of parts hereinafter more 15 particularly described, and then definitely pointed out in the claims.

In the accompanying drawings, Figure 1 represents a front elevation of a pair of eyeglasses provided with my improvement. Fig. 20 2 is a vertical central section of the same; Fig. 3, a front elevation of a modification; Fig. 4, a vertical central section of the same. Figs. 5, 6, and 7 are front elevations of other forms of nose-pieces detached.

25 All of the above are on a larger scale than the originals from which they are made, the better to show the small parts.

Referring now to the details of construction, A represents the frames, which are made 30 in any suitable or desirable form or material, to which is preferably attached the bar B, having at its free end a carrier C, preferably of spring metal, each of whose ends carries a nose-piece D, of rubber, cork, or other suitable material, which may be attached in any 35 desired way; but I prefer to attach them by means of thin plates E, fastened in any desired way to the ends of the carrier and having their sides turned up, so as to clamp the 40 the rubber or cork between said turned-up sides.

In the modification shown in Figs. 3 and 4 there is no bar B, the carrier being fastened directly to the frame. In Fig. 5 there is a 45 cross-bar b attached to the end of bar B, and to the ends of this cross-bar are attached coiled springs, the free ends of which carry the nose-pieces.

In Fig. 6 there is also a cross-bar attached

at the center to the main bar B, behind which 50 is a spring, substantially the same as carrier C in the other figures. To the opposite ends, of the spring are attached pins c, each of which carries a nose-piece.

In Fig. 7 there is another form of cross-bar, 55 which is provided with ears b', in which the nose-pieces are pivoted.

I do not intend to limit myself, except where especially claimed, either to spring, bendable, or rigid metal for the parts carrying 60 the nose-pieces, as either may be used, at the will of the manufacturer. In some cases the wearer may prefer that these parts be of spring metal, while others may prefer that the metal may be capable of being bent to suit 65 the nose and depend upon the bridge for the spring.

It is evident from the above that my invention may be varied in many ways without departing from the main feature of my invention, which consists in duplex or double nose-pieces—that is to say, nose-pieces having two 70 separate bearings on the sides of the nose.

The carrier may be attached to the bar B in any convenient manner; but I prefer to 75 attach it by a pivot or screw, for then the carrier may be adjusted at any convenient angle to the lens to suit the wearer's nose.

The carrier may, if preferred, be made in one piece with the bar, as shown in Fig. 7. 80

What I claim as new is—

1. Eyeglasses having duplex nose-pieces attached to a carrier having a central connection with the eyeglasses and adjustable at right angles to the lenses, substantially as 85 described.

2. The combination, with a pair of eyeglasses, of a bar B, a nose-piece carrier adjustably connected at its center with said bar B and carrying a nose-piece at each end, 90 substantially as described.

3. The combination, with a pair of eyeglasses, of a bar B, a nose-piece carrier adjustably connected to said bar B and having nose-pieces flexibly connected to each of its 95 ends, substantially as described.

4. The combination, with a pair of eyeglasses, of a bar B, a spring attached thereto,

and a nose-piece at each end of the spring, substantially as described.

5. The combination, with a pair of eye-glasses, of a bar B, a carrier C, and nose-pieces D, pivotally attached to each end of the carrier, substantially as described.

In testimony whereof I affix my signature,

in presence of two witnesses, this 20th day of March, 1889.

JOHN L. BORSCH.
